UNITED STATES PATENT OFFICE.

LESTER R. WELLMAN, OF CHICAGO, ILLINOIS, ASSIGNOR TO FRIEDELEY-VOSHARDT CO., OF CHICAGO, ILLINOIS, A CORPORATION OF ILLINOIS.

DESIGN FOR A PLATE FOR LIGHTING FIXTURES.

Application filed March 3, 1925. Serial No. 12,543. Term of patent 3½ years.

To all whom it may concern:

Be it known that I, LESTER R. WELLMAN, a citizen of the United States, residing at Chicago, in the county of Cook and State of Illinois, have invented a new, original, and ornamental Design for a Plate for Lighting Fixtures, of which the following is a specification, reference being had to the accompanying drawing, forming part thereof.

Fig. 1 is a fragmentary plan view show-

ing my new design, it being understood that the plate is circular and that the ornamentation is continued throughout the entire circumference.

Fig. 2 is a side elevation showing my new design.

I claim:

The ornamental design for a plate for lighting fixtures, as shown.

LESTER R. WELLMAN.
